UNITED STATES PATENT OFFICE.

WILLIAM HOCHHAUSEN, OF NEW YORK, N. Y.

HANGER-BOARD FOR ELECTRIC LAMPS.

SPECIFICATION forming part of Letters Patent No. 294,045, dated February 26, 1884.

Application filed August 6, 1883. (No model.)

To all whom it may concern:

Be it known that I, WM. HOCHHAUSEN, a citizen of the United States, and a resident of New York, in the county of New York and 5 State of New York, have invented certain new and useful Improvements in Hanger-Boards for Electric Lamps, of which the following is a specification.

My invention relates to apparatus for suspending and forming the electrical connections to electric lamps; and its object is to provide a simple and effective device whereby the lamp may be securely supported, and whereby, also, the main or principal circuit may be automatically preserved when the lamp is lowered and its connection with the main circuit broken.

My invention consists in certain novel combinations of devices and improvements in the details of construction, the nature of which 20 will be described in connection with the accompanying drawings, and will be specified in the claims.

In the accompanying drawings, Figure 1 is a vertical section, on the line 1. 1 of Fig. 3, 25 through the hanger-board; and Fig. 2 is a side view and partial section taken at right angles to Fig. 1. Fig. 3 is a plan view of the hanger-board, looking upward.

I have herein shown and described my invention as applied to an electric-arc lamp having two sets of carbons. The protecting-tubes for the upper-carbon carriers are shown in Fig. 2 at B B².

A indicates the top plate or cover for the 35 lamp mechanism, and I I² the ordinary insulated conductors by which current is conveyed to the lamp. The insulation is removed from the upper portion of these conductors, as shown in Fig. 2, so that they may form contact-plugs 40 adapted for insertion between the free end of a contact-spring and the surface of a plate against which said spring tends to bear.

C indicates a block of some suitable insulating material—such as wood—having upon its 45 bottom a circular groove, in which, at points corresponding to the position of conductors I I², are fixed two clamping posts or blocks, K K², adapted to receive the insulated line-conductors, and to hold them securely by means of 50 two set-screws. (Shown in Fig. 1.) The block C is provided with longitudinal perforations J in line with the sockets of the binding-posts,

to allow the line-wire to be inserted, and to also protect the bared ends of the line from accidental contact with foreign conductors. 55 The block C is also provided with openings or perforations N, by which it may be firmly secured to a ceiling or other support.

Attached to or formed upon the binding-posts K, and lying in the circular groove upon 60 the bottom of the block C, are two curved plates, R and M, resting against the periphery of a central boss or projection upon the bottom of the block C, and a spring, L, between which and the contact-piece upon the end of 65 plate R the end of the conductor I or I² may be forced when the lamp is raised into position, thus completing a connection with the line. The extreme end of spring L normally tends to 70 make connection with a curved plate, M², similar to M, and connected with the binding-post K², from which latter project the additional plate R² and a spring, L². Between the end of the latter plate and spring L² the end of the other lamp-conductor may be inserted, so as 75 to form connection with the binding-post K². The extreme end of the spring L² tends normally to make contact with the curved plate M.

The line-conductors being clamped in the two binding-posts, it will be readily seen that 80 if the lamp be lowered, so as to withdraw the conductors I I² from between the springs and the curved plates, the spring for each binding-post will, at its extremity, make contact with a curved plate connected with the other 85 binding-post, thus completing the connection directly between said posts and preserving the general line-circuit. When the lamp is raised, the ends of the conductors I I² are forced between the springs and the plates R² R, and 90 the extremities of the springs will be lifted out of connection with the plates M M², thus breaking the direct connection for the line-wire, and compelling the current to flow into the lamp through the conductors I I², which 95 are now in connection with their respective binding-posts.

D indicate two collars slipped upon the carrier-tubes B B² and clamped thereupon. These collars carry the eyes or guides a a, 100 which support the ends of the insulated conductors I² I. The collars D are connected by a piece, D², to which is secured a block, E, carrying the two pivoted catch-levers, F, hav-

ing at their upper ends the hooks $F^2 F^2$, which spring apart and catch upon the upper surface of the block C when the tubes B B² are raised to a sufficient distance through the central opening, B³, provided for them in the block C.

H indicates a metallic plate clamped to the top of the block C, and cut away, as shown in Fig. 1, to form depressions, into which the ends of the hooks F² enter, thus securely holding the latter until they are thrown back by pressure applied to the releasing-arms F³.

At G is indicated the spring which tends to force the hooks F F² outward when they have passed through the opening B³. The spring G connects the extensions F⁴ of levers F.

In the drawings the lamp is shown as suspended from the block C by the catch-levers.

To lower the lamp, it is merely necessary to apply upward pressure to the arms F³, thus drawing the upper ends of levers F inward, and at the same time lifting the parts so that the hooks may readily leave the depressions formed by the openings in the plate H.

I have herein shown my invention as applied to a double-carbon lamp; but it will be readily understood that the same may be also applied to a single-carbon lamp.

What I claim as my invention is—

1. The combination, with the carrier-tube for an electric-arc lamp, of a collar clamped upon the same, and a spring-catch supported by said collar and adapted to engage with the hanger board or support from which the lamp is to be suspended,

2. The combination of the hanger-board perforated for the carrier-tube, a catch or catches supported from said tube, for engaging with said board, and spring-switches upon the board adapted to receive the terminals of conductors leading into the lamp.

3. In a double electric lamp, the combination, with the collars D D, clamped to the carrier-tubes, and having eyes or rings that receive and support the lamp-conductors I I², of an intermediate connecting-piece, and an automatic catch pivoted from the latter, as and for the purpose described.

4. In a hanger-board for an electric lamp, the combination, with a block, C, perforated at its center, and provided with a circular groove upon its bottom, of the horizontally-movable connecting-springs lying in said groove.

5. The combination, with the insulating-block C, having annular groove on its bottom,

of the binding-posts seated in said groove, and a connecting spring and plate extending from each of said posts, and adapted to receive the terminals of conductors rising from the lamp.

6. The combination, with each of the two binding posts or blocks seated in the bottom of the hanger-board, of a horizontally-projecting spring and two horizontally-projecting plates, one of which on each of said posts forms, in connection with the spring, a connecting-clip for grasping the terminal of a conductor of the lamp, while the other plate forms an anvil or stop for the free end of the spring connected with the other post when the lamp is lowered.

7. In a hanger-board for an electric lamp, the combination of two binding posts or blocks, K' K², curved plates and springs extending from said blocks and lying in a circular groove in the bottom of the block, and conductors I I², rising from the lamp-casing.

8. The combination, with the hanger-board C, perforated at its center, of a binding-post, K, on the bottom of said board, horizontally-curved plates M R, curved around a central boss or projection, and spring I, between which and plate R the end of a conductor on the lamp may be forced, and a second post provided with a similar spring and plates, one of which latter forms a contact-stop for the free end of the spring connected with the first-named binding-post when the lamp is lowered.

9. The combination, with the block C of insulating material, perforated at its center, of the binding posts or blocks seated in a circular groove on the bottom of the board, and the longitudinal openings J, for the insulated line-wires.

10. The combination, with the hanger-board C, perforated at its center, and provided with means for completing the circuit to the lamp when the latter is raised to a sufficient distance, of the two catch-levers F F, carried by the lamp, the connecting-spring, and the releasing horizontal arms F³ F³, as and for the purpose described.

Signed at New York, in the county of New York and State of New York.

WILLIAM HOCHHAUSEN.
